DESIGN FOR AN AUTOGRAPHIC REGISTER

Harold Van Doren and Robert Deigert, Toledo,
Ohio, assignors to The Egry Register Company,
Dayton, Ohio, a corporation of Ohio

Application July 1, 1937, Serial No. 70,206

Term of patent 7 years

To all whom it may concern:

Be it known that we, Harold Van Doren and Robert Deigert, citizens of the United States, residing at Toledo, in the county of Lucas and State of Ohio, have invented a new, original, and ornamental Design for an Autographic Register, of which the following is a specification, reference being had to the accompanying drawing, forming a part thereof.

In the drawing:

We claim:
The ornamental design for an autographic register substantially as shown.

HAROLD VAN DOREN.
ROBERT DEIGERT.
